UNITED STATES PATENT OFFICE

114,956

DESIGN FOR A BADGE

Frank S. Land, Kansas City, Mo.

Application April 3, 1939, Serial No. 84,004

Term of patent 14 years

To all whom it may concern:

Be it known that I, Frank S. Land, a citizen of the United States, residing at Kansas City, in the county of Jackson and State of Missouri, have invented a new, original, and ornamental Design for Badges, of which the following is a specification, reference being had to the accompanying drawing, forming part thereof.

Fig. 1 is a front elevation of a badge showing my new design.

Fig. 2 is a side elevation of the same.

I claim:

The ornamental design for a badge, as shown.

FRANK S. LAND.
